UNITED STATES PATENT OFFICE.

HOWARD E. WATKINS, OF NEW YORK, N. Y., ASSIGNOR TO THE ENOS COMPANY, OF NEW YORK, N. Y., A CORPORATION OF NEW YORK.

DESIGN FOR A SHELL FOR LIGHTING-FIXTURES.

No. 39,705.

Specification for Design.

Patented Dec. 22, 1908.

Application filed September 5, 1908. Serial No. 451,910. Term of patent 14 years.

To all whom it may concern:

Be it known that I, HOWARD E. WATKINS, a citizen of the United States, residing in the city, county, and State of New York, have invented a new, original, and ornamental Design for Shells for Lighting-Fixtures, of which the following is a specification, reference being had to the accompanying drawing, forming a part thereof.

Figure 1 is a side elevation of a shell for

lighting fixtures, showing my new design, and Fig. 2 is a top view thereof.

I claim:

The ornamental design for shell for lighting fixtures as shown.

HOWARD E. WATKINS.
